(57) CLAIM

The ornamental design for a garment, as shown and described.

DESCRIPTION

FIG. 1 is a front view of a garment showing our new design. FIG. 2 is a rear view thereof.

FIG. 3 is a right-side view thereof.

FIG. 4 is a left-side view thereof.

FIG. 5 is a top view thereof; and,

FIG. 6 is a bottom view thereof.

The short broken lines show portions of the garment which form no part of the claimed design.

1 Claim, 5 Drawing Sheets
